ADVERTISING DISPLAY DEVICE

Milton K. Naylor, Three Rivers, Mich., assignor to
The Eddy Paper Corporation, Chicago, Ill., a
corporation of Illinois

Application July 29, 1935, Serial No. 33,655

8 Claims. (Cl. 40—124.1)

This invention relates to improvements in advertising display devices.

There is considerable demand at the present time for large sized, relatively inexpensive display signs of the easel supported type for use in garages, service stations, and the like. Heretofore, displays of this size, when manufactured of fiber board, paper board or corrugated material have been unsatisfactory. This is due to the fact that displays are usually placed in a window or other location where they are subjected to bright sunlight or to temperature conditions which produce warping and buckling.

It is one of the objects of the present invention to obviate the above mentioned objectionable feature by providing an advertising display or similar article wherein the upright panel is reinforced against warping in a simple and inexpensive manner.

A more specific object of the invention is to provide a device of the class described, constructed of fiber board, paper board, corrugated board or the like wherein the material of the panel itself is used to form the reenforcement.

A further object of the invention is to provide an improved display device which can be compactly shipped in flat form, and in which the easel and reenforcing portions can be quickly and easily assembled by the user.

A more specific object of the invention is to provide an advertising display device in which a rigidity in two directions may be obtained by using corrugated board and by having the corrugations extend in a direction at right angles to the direction of the reenforcements so that corrugations act to stiffen in the one direction, and the reenforcements in the other.

A further object of the invention is to provide an advertising display device having an improved form of easel support which is particularly adapted for supporting a display of large size.

With the above and other objects in view, the invention consists of an improved advertising display device and all its parts and combinations as set forth in the claims and all equivalents thereof.

In the accompanying drawing illustrating one complete embodiment of the preferred form of the invention, in which the same reference numerals designate the same parts in all of the views,

Fig. 1 is a rear view of the device in flat form for shipment;

Fig. 2 is a front elevational view thereof in assembled condition;

Fig. 3 is a perspective view looking from the rear showing the display in assembled form;

Fig. 4 is an enlarged fragmentary sectional view taken on line 4—4 of Fig. 3;

Fig. 5 is an enlarged fragmentary sectional view taken on line 5—5 of Fig. 3; and

Fig. 6 is an enlarged fragmentary sectional view taken on line 6—6 of Fig. 3.

Referring more particularly to the drawing, the numeral 8 designates the main panel which may be constructed of paper board, fiber board, corrugated board or any other suitable material. It is preferred to utilize corrugated board inasmuch as this material possesses additional advantages which will be hereinafter referred to. The material forming the main panel 8 is scored for folding near each longitudinal edge as at 9, 10, and 11.

The easel for supporting the display in upright position consists of an intermediate back portion 12 which is adhesively or otherwise connected to the panel 8, and side wings 13 which are foldable on lines of scoring 14. Locking tabs 15 and 16 are cut out from material forming the back 12 and wings 13 of the easel on lines 17 and 18 respectively, and said tabs are foldable to effective position on lines of fold 19 and 20 respectively. The tab 15 is formed with spaced slots 21 and the tab 16 with similar spaced slots 22. Each of the wings 13 is longitudinally scored for folding as at 23, to thereby provide edge flanges 24.

The displays may be shipped in quantities in the flat form shown in Fig. 1, and due to the large size of the displays, this possibility for compact shipment is an important feature. When the user receives a display, it is merely necessary for him to fold the edges along the lines 9, 10 and 11 to form a tubular triangular reenforcement along each edge in the manner shown in Figs. 3 and 4. Ordinary adhesive tape 25 may then be employed to maintain the folded reenforcement in position. The easel may be rendered operative by swinging the wings 13 toward one another on the fold lines 14 to the position shown in Fig. 3. Next, the tabs 15 and 16 are folded downwardly on the lines 19 and 20 and the slots 21 and 22 are caused to engage with the edges 26 and 27 of the recesses from which the tabs have been cut. The flanges 24 are then bent inwardly toward each other to the position shown in Fig. 3 to thereby add rigidity to the wings 13.

As before mentioned, it is preferred to utilize corrugated board for this type of display. Advertising displays for which this invention is par-

ticularly suited may be four or more feet in height and the maximum support against warping and bulging is necessary. By utilizing corrugated board, the corrugations 28 may be extended in a transverse direction (see Fig. 6) and this affords resistance to bending along a vertical line. Inasmuch as corrugated board possesses less resistance to bending in the other direction, that is, in a direction parallel to the corrugations, it is preferred to have the reenforcing members 29 extend in a direction at right angles to the direction in which the corrugations extend to thereby support the sign against bending in a direction parallel to the corrugations. Thus, the corrugated board and the reinforcements cooperate to produce an extremely rigid panel.

While it is in general necessary to use the reinforcement 29 only on the vertical side edges, 20 these reinforcements may of course be employed along other edges. For example, the upper edge portion 30 could be similarly reinforced and lower edge portions 31 and 32 on each side of the easel could be formed in a similar manner.

25 The front of the display may carry any desired advertising material 33 and the entire assemblage will form an impressive display of large size at the minimum of expense, and, due to the novel features of construction, be capable of 30 withstanding sunlight or temperature changes which might produce warping.

The type of easel disclosed, wherein the wings 13 are formed with bendable flanges 24, is particularly adapted for use in supporting a large sized display of this type, as the flanges 24 add rigidity to the wings to furnish ample support for the relatively heavy panel.

While the invention is more particularly adapted for advertising displays, the novel form of 40 reinforcement obviously has a wide adaptability and can be employed in any type of construction wherein it is desired to reinforce an edge portion of a panel of paper board or the like against bending or warping. The particular triangular 45 shape of the reinforcement can of course also be varied, and still accomplish a similar result, and all of such changes and modifications are contemplated as may come within the scope of the claims.

50 What I claim is:

1. A display device comprising a panel of bendable fibrous material, there being a plurality of spaced, parallel lines of scoring adjacent an edge of the panel to define a plurality of adjacent elongated sections, said sections being folded to form a tubular reinforcement for said edge, and means for securing said reinforcement in position.

2. A display device comprising a panel of bendable fibrous material, there being three spaced, parallel lines of scoring adjacent an edge of the panel to define three adjacent elongated sections, said sections being folded to form a tubular reinforcement for said edge, said reinforce-

ment being triangular in cross section, and means for securing said reinforcement in position.

3. A display device comprising a panel of bendable fibrous material, there being three spaced, parallel lines of scoring adjacent an edge of the panel to define three adjacent elongated sections, the outermost of said sections being folded behind the panel to a position parallel thereto, and the other two sections forming an angle with respect to the rear of the panel, and means for securing the reinforcement in position.

4. A display device comprising a panel of bendable fibrous material, there being three spaced, parallel lines of scoring adjacent an edge of the panel to define three adjacent elongated sections, the outermost of said sections being folded behind the panel to a position parallel thereto with its free edge abutting the innermost line of scoring, and the other two sections forming an angle with respect to the rear of the panel, and means for securing the reinforcement in position.

5. A display device comprising a panel of bendable fibrous material, there being at least three spaced parallel lines of scoring adjacent an edge of the panel to define a plurality of adjacent elongated sections, said sections being folded to form a tubular reinforcement for said edge, and means for securing said folded sections in reinforcing position.

6. A display device comprising a panel of bendable fibrous material, there being at least three spaced parallel lines of scoring adjacent an edge of the panel to define a plurality of adjacent elongated sections, the outermost of said sections being folded behind the panel to a position parallel thereto and the other sections forming an angle with respect to one another, and means for securing said folded sections in reinforcing position.

7. A display device comprising a panel of corrugated board having the corrugations extending in one direction, there being a plurality of spaced parallel lines of scoring adjacent an edge of the panel and extending transversely to the direction in which said corrugations extend to define a plurality of adjacent elongated sections, said sections being folded to form a tubular reinforcement for said edge which extends in a direction transversely to the direction in which the corrugations extend.

8. A display device comprising a panel of corrugated board, means for supporting the panel in a substantially upright position with the corrugations extending in a horizontal direction, there being a plurality of spaced parallel lines of scoring adjacent and parallel to an edge of the panel to define a plurality of adjacent elongated sections, said sections being folded to form a tubular reinforcement for said edge, which reinforcement extends in a direction at right angles to the direction in which the corrugations extend.

MILTON K. NAYLOR.
